2,620,291

1,2,3,4-TETRACHLOROBUTANE AS A BLACK
CARPET BEETLE LARVACIDE

Herbert L. Johnson, Media, and Archibald P. Stuart, Norwood, Pa., assignors to Sun Oil Company, Philadelphia, Pa., a corporation of New Jersey

Application December 26, 1947, Serial No. 793,800

2 Claims. (Cl. 167—22)

1

This invention relates to a novel larvacide and to a composition of which the larvacide is an essential ingredient.

The larvacide of this invention is 1,2,3,4-tetrachlorobutane, a chemical compound, which has been known in the chemical literature for some time. Thus, 1,2,3,4-tetrachlorobutane was first prepared by Henninger, Ann. Chim. (6), 7, 229 (1886). Another preparation of this compound has been described by Muskat & Northrup, J. Am. Chem. Soc. 52, 4043-4055 (1930). This preparation involves the chlorination of butadiene. At least two isomers of 1,2,3,4-tetrachlorobutane have been isolated. One isomer, a liquid (B. P. 110° C.-111° C. at 40 mm. Hg) and another a solid (B. P. 130° C.-134° C. at 40 mm. Hg, M. P. 72° C.) have been identified.

According to this invention we have found that both the solid and liquid forms or isomers of 1,2,3,4-tetrachlorobutane are useful as larvacides of an effectiveness not at all expected and indeed wholly surprising.

It is well known that carpet beetles are extremely difficult to kill, particularly is this so, because the materials heretofore used as a larvacide have been ineffective to produce a sufficient kill within a reasonably short time. This has allowed the larvae to develop an actual immunity resulting in almost all cases in a virtually complete failure or ineffectiveness of the materials employed. For a more complete résumé of just how serious the matter of finding an effective larvacide has been prior to this writing reference is made to the article entitled "Carpet-Beetle Control—Unsolved Wool Problem" by Henry N. Mitchell published in "Textile World" November 1946, pages 170, 221 and 222.

It is generally believed that p-dichlorobenzene is a superior larvacide particularly against the carpet beetle. So far is this true that the official test larvacide now employed by the commercial testing laboratories is p-dichlorobenzene. It is to be noted that compounds having a rather good kill of the carpet beetle are extant. However, these have properties which prohibit their use, particularly for domestic purposes. It is well known that additionally to kill, a larvacide must not have a disagreeable vapor or odor and particularly that its vapor must be non-poisonous to humans.

Comparison of the results of tests made using p-dichlorobenzene, on the one hand, and the tetrachlorobutane of this invention, on the other, made in the table below clearly shows the greatly superior quality of tetrachlorobutane whether its solid or liquid form is used.

2

The test procedure employed was as follows:

A two mg. of sample and of p-dichlorobenzene was weighed into separate half gallon bottles, and the bottles quickly corked. A ventilated capsule containing fifty of the *Attagenus* larvae and a one square inch disc of cream flannel test cloth was suspended from each cork near the center of the bottle.

The bottles were kept in an incubator at 78° F.-80° F. for two weeks. They were inverted twice daily for several days to distribute the fumes. The test sample and the p-dichlorobenzene vaporized completely within two days.

The cloth discs were examined for injury at the end of the two weeks, and the insects were removed to recovery dishes. Four weeks later, live and dead insects were counted.

Some test results obtained are summarized in the table.

Compound	Conc'n mg. per liter	Percent Kill	Percent Kill of p-dichlorobenzene at same conc'n
Solid C ₄ H ₈ Cl ₄	1.1	30	10
Do.....	1.6	62	12
Liquid C ₄ H ₈ Cl ₄	2.2	100	66

In the figure of the drawing there is shown a plot of the comparative insecticidal action of 1,2,3,4-tetrachlorobutane, on the one hand, and p-dichlorobenzene, on the other, against the "yellow" *Attagenus* (black carpet beetle) larvae. It is at once apparent from the graph that 1,2,3,4-tetrachlorobutane is vastly superior in kill to p-dichlorobenzene against the larvae. Thus, tetrachlorobutane will kill from 50% (at total kill) to 400% (at low kill) more larvae under the same conditions as will p-dichlorobenzene. It follows that much less 1,2,3,4-tetrachlorobutane is required to give the same degree of kill as p-dichlorobenzene.

The larvacide of this invention can be made up for use in solution and applied in effective concentration to the material to be protected. Thus, the larvacidal ingredient of this invention can be applied to materials during a dry cleaning operation employing any desired effective concentrations of the tetrachlorobutane in a dry cleaning solvent such as dry cleaning naphtha (Stoddard solvent) or the halogenated dry cleaning solvents. Obviously, the more concentrated the solution the greater will be the quantity of tetrachlorobutane deposited in the material. The liquid tetrachlorobutane is substantially infinitely soluble in

solvents such as carbon tetrachloride, trichloroethylene and dry cleaning naphthas. The solid form is also soluble in these solvents, though to a lesser extent which however is great enough to allow for proper larvacidal protection to be imparted during dry cleaning employing these solvents. The larvacidal composition of the invention can also take the form of a sub-divided solid admixture of the solid tetrachlorobutane with an inert solid carrier or the form of a sub-divided inert carrier which has been contacted or impregnated with the liquid tetrachlorobutane. Such solid carriers may be, pyrophyllite, talc or other well known insecticide carriers.

We claim:

1. The method of controlling damage by larvae which comprises applying 1,2,3,4-tetrachlorobutane to loci infested with black carpet beetle larvae.
2. The method of controlling damage by larvae

10 5

which comprises contacting, within a confined space, vaporized 1,2,3,4-tetrachlorobutane with loci infested with black carpet beetle larvae.
